UNITED STATES PATENT OFFICE.

FRANK M. STEINER, OF MINNEAPOLIS, MINNESOTA, ASSIGNOR, BY MESNE ASSIGNMENTS, TO STEINER SALES COMPANY, OF SALT LAKE CITY, UTAH, A CORPORATION OF UTAH.

TOWEL CABINET.

Application filed May 24, 1920. Serial No. 383,781.

To all whom it may concern:

Be it known that I, FRANK M. STEINER, a citizen of the United States, resident of Minneapolis, county of Hennepin, State of Minnesota, have invented certain new and useful Improvements in Towel Cabinets, of which the following is a specification.

The object of my invention is to provide a towel cabinet from which all gears, rolls 10 and other devices which add to the expense of the cabinet are eliminated.

A further object is to provide a cabinet adapted to receive the bolt of toweling 15 folded as it comes from the mangle for delivery to the user, and thereby the labor and time required for winding the towel on a roll is avoided.

A further object is to provide a cabinet 20 of such construction that the clean portion of the towel can not possibly come in contact and be contaminated by the soiled portion of the towel.

A further object is to provide a cabinet 25 which will be easily accessible for the purpose of placing a clean towel therein and which will allow the convenient removal of the soiled towel.

Other objects of the invention will appear 30 from the following detailed description.

The invention consists generally in various constructions and combinations, all as 35 hereinafter described and particularly pointed out in the claims.

In the accompanying drawings forming 40 part of this specification,

Figure 1 is a vertical sectional view through a towel cabinet embodying my invention,

Figure 2 is a front elevation of the cabinet 45 net.

Figure 3 is a sectional view of a cabinet embodying a modified construction,

Figure 4 is a similar view, showing the 50 bolt of toweling wound on a roll instead of folded back and forth upon itself within the compartment of the cabinet.

In the drawings, 2 represents a suitable cabinet of wood, having a closed top and bottom and side walls and adapted to be 55 mounted on a suitable support. Within this

cabinet is a space or compartment 3 that is adapted to receive the bolt of toweling 4 folded as discharged by the ironing machine for delivery to the customer. The towel in this folded form is delivered by 55 the laundry to the place where the cabinet is located and inserted into the chamber or compartment, all without the necessity of refolding or winding the towel on a roll, as 60 frequently is done.

A partition 5 forms one side wall of the compartment and over this partition one end of the towel is fed between the partition and a door 6 that forms the front of the cabinet and through which, when open by turning 65 on the hinges shown in Fig. 2, the clean towel is inserted. A weighted arm 7 is hinged at 8 on the rear wall of the cabinet and is adapted to rest on the upper end of the partition 5. This arm serves to retard 70 the feed of the towel and provides sufficient friction to prevent the towel from sliding out of the compartment when the door of the cabinet is open. Pressure springs 9 are mounted on the door and adapted to bear on 75 the towel and hold it against the partition 5 with sufficient friction to resist any unnecessary or unusual feed of the towel when the cabinet is in use.

I prefer also to place a bracket or plate 80 10 on the lower end of the door adapted to engage the towel and press it inwardly so that when the used portion of the towel is released, it will be directed into the receptacle 11 beneath, where the towel will accumulate until entirely used and then be removed and taken back to the laundry.

The receptacle 11 preferably has an inclined forward wall 12 to provide a wide mouth or opening for the receptacle and 90 preferably projects beyond the front of the cabinet so that when the user releases the towel it will drop by gravity into the receptacle and the inwardly projecting bracket 10 will aid in keeping the clean portion of 95 the towel out of contact with the soiled portion.

In using the device, the folded bolt of clean toweling will be placed in the compartment 3 and one end carried over the parti- 100

tion and down between the partition and the wall of the cabinet. The lower end of the towel will be grasped by the user and pulled out of the cabinet and when used will be dropped and allowed to fall into the receptacle beneath. The weighted arm and the springs will resist sufficiently to feed the towel so that only such length as the user needs will be delivered. When the door is opened for any purpose, the weighted arm will be sufficient to prevent the towel from sliding out of the cabinet.

In Figure 3 I have shown a casing 13 having a partition 5^a therein corresponding to the one described with reference to the other figures and a chamber 3^a in which the folded bolt of toweling is placed, the free end of the toweling being carried over the partition 5^a down through the space 13 in the rear of the partition and through an opening 14 in the bottom of the casing. The sliding of the towel out of the casing is prevented by the weighted arm 7^a that is mounted in the top of the cabinet and has a lower portion that is adapted to bear on the toweling. Access to the cabinet may be had in any suitable way, by means of a door in the top or side walls, as preferred. The receptacle beneath corresponds to the one described and I will indicate it by the same reference figures.

The principal difference in the two constructions is that the partition is in the rear of the cabinet so that the toweling is delivered adjacent the rear wall instead at the front of the cabinet. The towel, when used, is allowed to drop into the receptacle beneath and a clean portion will always be within convenient reach of the person standing in front of the cabinet.

In Figure 4 a similar construction is shown, except that the bolt of toweling instead of being folded back and forth as it comes from the ironing machine, is wound on a roll 15 that is supported by a suitable means within the casing where it may deliver the end of the towel in the rear of the partition to a point where the user may conveniently grasp it and unwind a sufficient amount for his needs.

A similar weighted arm 7^a is shown mounted in the top of the casing and adapted to bear on the bolt of toweling as it passes over the rear partition.

In all these constructions simplicity of construction is a predominating feature. Gears, drive belts and operating mechanism of various kinds have been eliminated, it being only necessary in filling the cabinet to place the folded bolt of toweling therein, extend the loose end over the partition to a point where it can be conveniently reached by the user, close the door of the cabinet and the device is ready for use. This bolt of toweling forms in effect a series of individ-

ual towels joined together. It is the most convenient and cheapest form of towel to handle in the laundry. It is not necessary to wind it on a roll and it may be placed in the cabinet in folded form as delivered by the 70 ironing machine.

I claim as my invention:

1. A towel cabinet comprising a casing having a space therein to receive a bolt of toweling, a wall mounted in said casing and 75 over which the loose end of the bolt of toweling is fed, a door having means for normally pressing the toweling against said wall to resist feed of the toweling, an arm mounted to bear on the toweling, and check 80 the feed thereof when the door is open, the loose end of the bolt of toweling depending outside the casing within convenient reach of the user and falling in folds below the cabinet as the toweling is used.

2. A towel cabinet comprising a casing having a door in the front thereof and a space within the casing adapted to receive a bolt of toweling, a guide interposed between said door and the space for the toweling and over which the loose end of the toweling is fed to the user, said door having means thereon for exerting a yielding pressure on the towel to prevent premature feed thereof, the towel being delivered by the pull of 95 the user thereon.

3. A towel cabinet comprising a casing, a door therefor, said casing having a space therein to receive a bolt of toweling, the free end of the towel being fed from said casing 100 between said space and door, a soiled towel receptacle wherein the towel falls when released by the user, and means adjacent said casing for pressing the loose depending end 105 of the towel inwardly so that when the web of towel below said pressing means is used and released, it will be directed into said receptacle.

4. A towel cabinet comprising a casing 110 adapted to be supported on the wall and having a floor, rear, and side walls a front door and a closed top, said floor having a gap or opening therein at one side, an upright partition on said floor adjacent said gap, between which upright partition and the front door of said casing a chamber for the clean towel bolt is formed, the web of clean towel resting on the upper edge of said partition and passing down through said gap to a 115 point within convenient reach of the user, and an arm pivoted at one end in said casing and adapted to rest by gravity at its other end over the partition upon the web of towel the end of said arm being supported by said partition, the weight of said arm on said towel resisting its sliding movement on said partition and retarding the delivery of the clean web of towel.

5. A towel cabinet comprising a casing 120 having a compartment adapted to receive a

bolt of toweling, a wall mounted vertically in said compartment and projecting above the bolt of toweling therein, said wall having an upper edge on which the free end of the bolt of toweling is adapted to rest and slide, and said cabinet having a space and an opening on the opposite side of said wall from the bolt of toweling through which the loose end is adapted to depend within con-

venient reach of the user, a door forming 10 the outer wall of said space, and means mounted on said door for pressing the toweling against the said wall to yieldingly resist the too rapid feed of the towel from the cabinet. 15

In witness whereof, I have hereunto set my hand this 19th day of May 1920.

FRANK M. STEINER.
